US0D1015819S

(12) **United States Design Patent** (10) **Patent No.:** **US D1,015,819 S**
(45) **Date of Patent:** **** Feb. 27, 2024**

(54) **COFFEE BEVERAGE RAPID COOLER**

(71) Applicant: **Ningbo Holy Bull Plastic Industry Co., Ltd., Zhejiang (CN)**

(72) Inventor: **Lei Wang, Zhejiang (CN)**

(**) Term: **15 Years**

(21) Appl. No.: **29/832,947**

(22) Filed: **Mar. 31, 2022**

(30) **Foreign Application Priority Data**

Dec. 13, 2021 (CN) 202130821711.6

(51) **LOC (14) Cl.** **07-10**

(52) **U.S. Cl.**

USPC **D7/608; D7/602; D7/605**

(58) **Field of Classification Search**

USPC D7/313, 320, 511, 515, 531, 532, 601,

D7/602, 605, 606, 607, 608, 620;

(57) **CLAIM**

The ornamental design for a coffee beverage rapid cooler, as shown.

DESCRIPTION

FIG. 1 is a front elevational view of a coffee beverage rapid cooler showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is a second perspective view thereof.

1 Claim, 8 Drawing Sheets
